UNITED STATES PATENT OFFICE.

ISRAEL KUSSNER, OF NEW YORK, N. Y.

TOY CONSTRUCTOR.

Application filed October 7, 1922. Serial No. 593,095.

To all whom it may concern:

Be it known that I, ISRAEL KUSSNER, a citizen of the United States, and a resident of New York, in the county of New York and State of New York, have invented a new and Improved Toy Constructor, of which the following is a full, clear, and exact description.

The object of this invention is to provide a new article of manufacture constituting a toy in the nature of a card-house-constructor clip, formed of a unitary piece of material and having a plurality of leaves arranged in different angular relations, and with one, a plurality or all of such leaves equipped with resilient tongues or similar gripping means, each to engage a marginal portion of a card. Such card may be of any size or shape, although preferably the invention is used by the child in connection with the various cards of an ordinary deck of playing cards, where the similarly decorated backs of the cards will permit the construction of devices of various sizes, shapes and structural features with a general exterior color scheme which is attractive and consistent throughout. Obviously, however, the particular kind of card to be employed is secondary to the main idea of the invention, and specially cut cards of various colors and sizes may be employed some of which may desirably be of triangular or other polygonal outline as well as quadrangular.

The invention will be more clearly understood from the following description, when taken in connection with the accompanying drawing, showing various preferred embodiments of the new toy-constructor-clip, which clip will hereinafter be referred to for purposes of convenience merely as "the clip".

In this drawing:

Fig. 1 is a perspective view of a card house constructed by the use of a plurality of the clips shaped to constitute various of the multitudinous possible modifications of the latter, some clips in this view being indicated only diagrammatically in dot-and-dash lines, but nevertheless to show clearly the various angular relations in which the clip leaves may be disposed; it being noted in this connection that the showing of Fig. 1 is nevertheless incomplete so far as showing the incorporation in such

card house structure of all the said preferred embodiments, the clips the locations of which are indicated in Fig. 1 being variations merely of an embodiment of the clip having but two leaves;

Fig. 2 is a plan view of an incomplete embodiment of a clip of the present invention belonging to the class of clips indicated diagrammatically in Fig. 1 as just explained, said embodiment being incomplete because Fig. 2 shows the clip before the same is bent along the dot-and-dash lines of Fig. 2 to dispose the leaves of the clip in planes one disposed at an angle to the other, and thus the clip of Fig. 2 does not, until so bent, represent truly such embodiment;

Fig. 3 is a side elevation of the clip of Fig. 2, bent as just described, and hence constituting truly one embodiment of the invention;

Figs. 4 and 5 are respectively what may be termed top plan and front elevational views of another embodiment of the invention, having more than two leaves and differing further from the clip of Fig. 3 in that certain of said leaves are arranged side by side in the same plane, so that this clip may conveniently be used for joining a plurality of cards in the same plane, while supporting said cards on a suitable support independent of other cards, as in laying the foundation for the house or in building a fence, corral or the like;

Fig. 6 is a perspective view of an embodiment of the invention of the general type shown in Figs. 1 and 3, but constructed of sheet rather than wire material; and

Figs. 7 and 8 are views respectively similar to Figs. 4 and 5, and showing a clip similar to the clip shown in the latter figures, but also constructed of sheet rather than wire material.

Similar reference characters refer to similar parts throughout the several views of the drawing.

Referring to the details of the drawing, it will be seen that each clip, however embodied, includes a plurality of leaf members indicated at L in Fig. 1, at L² in Figs. 2 and 3, at L⁴ and L⁵ in Figs. 4 and 5, at L⁶ in Fig. 6, and at L⁷ and L⁸ in Figs. 7 and 8.

It will be understood from what has been said that the clips shown in association

with the building cards C of Fig. 1 may be either clips like those of Fig. 3 or clips like those of Fig. 6, so that the edge portions of the various cards will be resiliently gripped by the tongues T^2 of leaves L^2 of Figs. 2 and 3, or by the tongues T^6 of the leaves L^6 of Fig. 6, in an instantaneously attachable and detachable manner. It will be clear that these tongues, when carried as explained by their leaves, may be termed the card grips.

The double-headed arrows X of Figs. 3 and 6 indicate an important feature of the invention, which is this, that although each 15 clip, to constitute an embodiment of the invention as at present completed, must have its leaves in angularly separated planes, the degree of such angular separation is unimportant as long as it is under precisely 20 180° . Thus, the angle X in both Figs. 3 and 6 may be such that the leaves of the clip establish between them an acute angle, a right angle, or an obtuse angle.

It will be seen that the clip of Figs. 2 and 25 3 is constructed of a unitary bent length of wire 9, and that the clip of Fig. 6 is constructed of a unitary sheet of material 10. The wire 9 is, of course, preferably metal; but the sheet 10 may be of metal, cel- 30 luloid, or other suitable material.

As was said above, the clips of Figs. 4 and 5 and Figs. 7 and 8 are provided for other structural purposes than those illustratively indicated in Fig. 1, that is, for fa- 35 cilitating the erection of foundation walls, fences or the like, where the cards gripped by these clips are supported by a table top or the like and not by connection with other cards by way of a clip or clips.

40 These clips of Figs. 4 and 5 have, in addition to card-engaging or tongue-equipped leaves L^4 , plain leaves L^5 not equipped with tongues but to constitute supporting base portions for the clip to permit the same to stand upright on its own base on a table top or other suitable support.

45 The clips of Figs. 7 and 8 have leaves L^7 similar in equipment and function to the leaves L^4 of Figs. 4 and 5, and leaves L^8

without tongues and to constitute base por- 50 tions for the clip and so act similarly to the leaves L^8 of Figs. 4 and 5.

It will be seen that the clip of Figs. 4 and 5 and the clip of Figs. 7 and 8 are similar, respectively, to the clip of Fig. 3 and the 55 clip of Fig. 6; in that, while the clip of Figs. 4 and 5 is constructed of a unitary bent length of wire 12, the clip of Figs. 7 and 8 is constructed of a unitary sheet of any suitable material 13.

In the case of the clip of Fig. 6, it will be seen that the same has its tongues T^6 so cut that they are staggered on opposite sides of the line of bend 14, as otherwise the tongue roots could not be brought all the way to 65 such line of bend, without losing the two tongues.

In the case of the clip of Figs. 7 and 8, it will be seen that the tongues T^8 of the leaves L^7 , as well as the basal leaves L^8 are all 70 struck from a single strip of sheet material 13; the parts L^8 thus themselves being really tongues but permanently bent at right angles to the strip as indicated.

Inasmuch as various changes might be made 75 in the general form and arrangement of the parts described without departing from the invention, I do not limit myself to the precise details set forth, but consider myself at liberty to make such changes and alterations 80 as fairly fall within the spirit and scope of the appended claims.

I claim:

1. A card coupling device of the character described, consisting of a single piece of 85 wire having nested jaws at its respective ends and having its intermediate portion located diagonally relative to the jaws and bent whereby the nested jaws are at an angle to each other.

2. A card coupling device of the character stated, consisting of a single piece of wire having a pair of triangular-shaped jaws at both ends and the connecting run of wire located diagonally relative to the jaws and 95 bent whereby the pairs of jaws are at an angle to each other.

ISRAEL KUSSNER.
